UNITED STATES PATENT OFFICE

2,466,909

AUTOMATIC CLAMP

Glenn W. Periman, Los Angeles, Calif., assignor to
 Aircraft Tools, Inc., Los Angeles, Calif., a corporation of California

Application June 12, 1948, Serial No. 32,671

4 Claims. (Cl. 24—263)

1

This invention relates to clamps, generally, and more particularly to a C-clamp that is automatic to grip material between the jaws thereof after said jaws are separated and then released.

An object of the present invention is to provide a C-clamp of the character indicated that embodies one fixed jaw and an opposed spring-urged jaw that automatically seeks clamping engagement with the fixed jaw.

Another object of the invention is to provide, in a C-clamp as referred to, a slidable jaw that is spring-urged to seek a work-clamping position.

My invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a side elevational view, partly in longitudinal section, of a C-clamp according to the instant invention.

Fig. 2 is a plan sectional view as taken on line 2—2 of Fig. 1.

The illustrated embodiment of the clamp comprises, generally, a frame 5, a stem 6 extending from said frame and terminating in a knob 7, a slidable member 8 telescopically engaged with the stem, and a spring 9 for moving said member to effect clamping of work W between it and the frame.

The frame 5 is C-shaped and is integrally formed with spaced substantially parallel arms 10 and 11 that are connected by a portion 12. The frame thus formed is substantially rigid, although slight flexure of the arms, relatively, is immaterial. In its present form, the end of arm 10 is integrally formed with a jaw 13 that faces in the direction of arm 11. The end of the latter arm is provided with a through bore 14 for the stem 6.

The stem 6 comprises a preferably round rod or bar 15 that has a reduced portion 16 residing in bore 14. The shoulder 17 thus formed and the staked end 18 of the stem serve to rigidly mount the stem on the frame so that the former

2

extends outwardly normal to arm 11 and, if extended, would pass through jaw 13. The outer end of stem 6 is formed or provided with knob 7 and said knob has a somewhat domed top 19 to comfortably receive hand or finger pressure, although equally adapted to receive the pressure of one jaw of a tool. Said tool forms no part of this invention and is not shown. However, the same will be more fully described hereinafter.

The member 8, at one end, is integrally formed with a jaw 20 that is opposed to jaw 13, has an integral section 21 of some length in which the end 22 of arm 11 resides, and beyond said section 21, has an integral tubular part 23. The latter is formed with an outwardly facing cylindrical seat 24 for spring 9, said spring having end engagement with a transverse abutment wall 25. The latter wall is formed with a hole 26 through which the stem 6 passes. The tubular form of part 23 extends through and is continued in section 21, except that said section is open laterally as at 27 to accommodate arm 11 of the frame.

In practice, the part 23 is reduced in size at an intermediate part 28 to form an annular shoulder 29. However, this shoulder may be formed in other ways.

The spring 9 is of the coil type and has its ends confined between abutment wall 25 and knob 7. Consequently, said spring, at all times seeks to expand and urge jaw 20 toward jaw 13. The expansive force of the spring is such that said jaws engage with sufficient pressure to clamp work 22 between them.

The tool above-mentioned is well known and is shaped in the manner of pliers with one jaw bifurcated. In use, said tool is applied with the bifurcated jaw engaged with shoulder 29 and the other jaw engaged with the top of knob 7. By applying a force to close the jaws of the pliers, the spring 9 is further compressed and the member 8 is slid along stem 6 to effect separation of jaws 13 and 20. When the jaws are so opened, work may be placed between them. Upon release of the plier jaws, spring 9 becomes again effective to automatically move jaws 13 and 20 toward each other and thereby clamp work under pressure of the compressed spring 9. The clamp above set forth may, of course, be entirely manually operated, providing, however, that the clamp is not of such large size and the spring of such great force that such manual operation is precluded.

While I have illustrated and described what I now regard as the preferred embodiment of my invention, the construction is, of course, subject to modifications without departing from the

spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. A clamp comprising a C-frame formed with substantially parallel spaced arms the end of one arm comprising a clamp jaw, a stem extending from the end of the other arm and provided with a knob at the outer end thereof, a member slidably mounted on the stem and having a jaw at that end which is directed toward the jaw on the frame, and a coil spring around the stem having one end abutted against the member and the other end against the knob for urging said member in a direction to close the jaws.

2. A clamp comprising a C-frame formed with substantially parallel spaced arms the end of one arm comprising a clamp jaw, a stem extending from the end of the other arm and provided with a knob at the outer end thereof, a member slidably mounted on the stem and having a jaw at that end which is directed toward the jaw on the frame, and a coil spring around the stem having one end abutted against the member and the other end against the knob for urging said member in a direction to close the jaws, said slidable member having the end opposite to the jaw formed with an outwardly facing cylindrical seat for housing at least part of said spring.

3. A clamp comprising a C-frame formed with substantially parallel spaced arms the end of one arm comprising a clamp jaw, a stem extending from the end of the other arm and provided with a knob at the outer end thereof, a member slidably mounted on the stem and having a jaw at that end which is directed toward the jaw on the frame, and a coil spring around the stem having

one end abutted against the member and the other end against the knob for urging said member in a direction to close the jaws, said slidable member, on the end opposite to the jaw, being provided with a shoulder whereby a tool engaged with said shoulder and with the knob is adapted to slide the slidable member against the force of the spring toward the knob and thereby separate the jaws.

10 4. A clamp comprising a C-frame formed with substantially parallel spaced arms the end of one arm comprising a clamp jaw, a stem extending from the end of the other arm and provided with a knob at the outer end thereof, a member slidably mounted on the stem and having a jaw at that end which is directed toward the jaw on the frame, and a coil spring around the stem having one end abutted against the member and the other end against the knob for urging said member in a direction to close the jaws, said slidable member, between its jaw and the spring abutment thereof being formed with a laterally open elongated portion to accommodate that portion of the frame arm that carries the stem.
